UNITED STATES PATENT OFFICE.

CHARLES LOUIS RAGOT, OF MILFORD, PENNSYLVANIA, ASSIGNOR OF ONE-THIRD TO LOUIS F. RAGOT, OF MILFORD, PENNSYLVANIA.

INTERNAL-COMBUSTION ROTARY ENGINE.

1,088,623.

Specification of Letters Patent. Patented Feb. 24, 1914.

Application filed July 14, 1911. Serial No. 638,496.

To all whom it may concern:

Be it known that I, CHARLES LOUIS RAGOT, a citizen of the United States, and a resident of Milford, in the county of Pike and State of Pennsylvania, have invented a new and Improved Internal-Combustion Rotary Engine, of which the following is a full, clear, and exact description.

My invention relates to internal combustion rotary engines admitting of general use, and more particularly to a type of such engine which, because of its lightness, strength, smooth running, reliability, simplicity and various other qualities, enable it to be used in connection with flying machines.

More particularly stated my improved internal combustion rotary engine is a device by aid whereof I seek to accomplish the following purpose, to wit:—I. To utilize the explosive force of explosions by directing them against pistons which are provided with portions engaging the inner surface of a stator consisting of an elliptical track which guide the pistons to perform four cycles in one revolution and serve as a cam for turning a rotor having radial cylinders in which the pistons travel. II. To dispose passages in a revolving central drum coating with parts in a stationary stator frame to introduce explosive charges, ignite and scavenge them. III. To enable a single spark plug and a single ignition chamber to be used in connection with a number of separate cylinders. IV. To provide improved means for cooling the rotor and particularly the parts thereof immediately affected by the explosions. V. To facilitate the circulation of water through the rotor in order to effect the cooling of the same and parts associated with it. VI. To use ball bearings and parts associated therewith to alleviate the friction between the outer ends of the pistons and the adjacent track of elliptical form. VII. To improve the various parts for the purpose of promoting simplicity, lightness, smooth running, strength and durability coupled with efficiency in adapting the device for the purpose for which it is intended.

Reference is to be had to the accompanying drawings forming a part of this specification in which like characters of refer-

ence indicate corresponding parts in all the views, and in which—

Figure 1 is an elevation showing the elliptical stator frame and the rotor carrying the cylinders and revolvably mounted within said frame, the face spider of the frame, however, being removed; Fig. 2 is a substantially central vertical section through the engine as shown in Fig. 1; Fig. 3 is a detail showing, in cross section, the end view of the gas chambers in the rotor drum and the relative position of the parts for admitting, firing and releasing the gases. Fig. 4 is a detail showing a part of the water extractor for circulating cold water through the rotor and water cooling radiator

A stator frame 6 having generally an elliptical form is provided with bracket arms 7 by aid whereof it may be mounted upon the framework, say, of a flying machine. The stator frame 6 is stationary and is provided with spokes 8 integral with it, these spokes being connected rigidly with a barrel 9, the form of which can be understood from Fig. 2. The end of the barrel 9 opposite the spokes 8 is enlarged, and connected with this end is a bearing ring 10 constituting in effect, a ball race.

A propeller is shown at 11 and is provided centrally with an opening 12. The propeller carries a cap 13 which fits over the opening 12 and is held in position by aid of bolts 14 which extend through the propeller and are located upon opposite sides of the opening 12. A bearing ring 15 is disposed in juxtaposition to the bearing ring 10, and between these two bearing rings are rolling bodies 16 constituting, with the bearing rings, a ball bearing. Encircled by the barrel 9 and the bearing ring 10 is a sleeve 17 of cylindrical form which is fixed relatively to the stator frame 6. Inside this sleeve and concentric to the same is a sleeve 18 which is carried upon a revolvable drum 19. This drum is provided with a neck 20 threaded externally and fitted into a thimble 21 carried by the bearing ring 15 and integral therewith, this thimble being threaded internally. The propeller 11, bearing ring 15, including its thimble 21, and the drum 19 including its neck 20 and the sleeve 18, are all adapted to turn as a unit

relative to the bearing sleeve 17, the bearing ring 10 and the spider 8 of the stationary stator frame. The drum 19 is provided with a number of cylinders 22 all exactly alike, and in this instance integral with each other, these cylinders extending radially outward from the drum. Each cylinder 22, at its inner end, merges into a substantially horn-shaped wall 23 provided with a passage 23^a having substantially the form indicated in Fig. 2, the inner end of the passage, however, being flared slightly in the direction of the general plane of rotation, as indicated at 23^b in Fig. 3. The drum 19 is further provided with a convex portion 24, the latter having a cylindrical extension 25 and a stuffing box 26.

Extending through the stuffing box 26 is a tube 27 provided with a closed end 28. A water pipe 29 extends centrally through the tube 27 to a point within the neck 20. The inner end of the tube 27 is provided with a number of short pipes 30 all bent spirally, as indicated in Fig. 4, and communicating with the tube 27, and through the medium of this tube with another pipe 31. The purpose of this arrangement is to create a circulation of water through the drum 19 which, for this purpose, is rendered hollow, as will be understood from Fig. 2. The drum normally contains water as will be understood from Figs. 2 and 3. As the drum turns, this water is carried bodily around, and owing to the spiral form of the pipes 30 (which are stationary) is forced rapidly through these pipes and thus produces within the tube 27 a pressure which causes the water to pass straight through this tube and into the pipe 31, the water being led back by any appropriate connections through a water cooling radiator and the pipe 29, is conducted back toward the propeller to a point within the threaded neck 20, and thence works forward again through the pipes 30. The water is thus circulated continuously through the drum 19 while the machine is in action. Moreover, the velocity of the water is comparable with the speed of the drum 19, as this drum is turned, at different rates of speed.

Fitted into each cylinder 22 is a piston 32 which is provided with piston rings 33 and with ventilation holes 34, as will be understood from Fig. 2. Each piston 32 at its outer end, has in this instance a frusto conical form and carries a circular disk 35. This disk is, by aid of pins 36 and 37, fixedly connected with the outer end of the piston. The circular disk 35 is fashioned into a ball race and is engaged exteriorly by a number of balls 38. Surrounding these balls is a ring 39, the inner surface of which is fashioned into a ball race, the outer surface serving simply the purpose of a wheel. There are, of course, as many of these wheels as there

are pistons. Each wheel 39 engages a track 40 made of durable material, in this instance, fiber. This track is fixedly mounted upon the stator frame which is recessed in order to receive it, as will be understood from Fig. 2. The general shape of the track 40 is elliptical; that is, it has two short radii and two long radii. The stator frame 6 is further provided with a groove 41, the general form of which is elliptical. Each piston 32, adjacent to its outer end, carries a roller 42, the latter being mounted upon the pin 37 and fitting into the elliptical groove 41. There are as many rollers 42 as there are pistons, each roller serving to guide and steady the piston with which it is associated, and further serving to keep the pistons along the elliptical track when starting the motor so the radial bearings will keep in the line of rotation.

The ignition chamber is shown at 43 in Fig. 3, and is provided with a hand valve 44 and also with a water jacket 45 and a spark plug 46. The operator, by opening the hand valve 44, may allow the explosion to take place in the air and thereby stop the engine or curtail its power to any desired degree should occasion arise for so doing in case of emergency. Said water jacket forming part of same water circuit as the radiator and rotor through the necessary piping.

The intake pipe is shown at 47 in Fig. 3 and is connected directly to the carburetor which may be of any suitable form. The exhaust pipe is shown at 48, and in this instance, opens directly into the atmosphere. It may, however, be directly connected with a muffler.

Referring more particularly to Fig. 3, attention is called to the relative proportioning of the parts shown in said figure. The several horn-shaped passages 23^a are respectively flared, as shown at 23^b, to such an extent that the intervening portions of the drum 19 are just sufficient to span across the openings in the intake pipe 47 and exhaust pipe 48. The parts are also proportioned so that the flare of each passage 23^b is just sufficient to span the distance between the intake pipe 47 and the exhaust pipe 48. The timing of the spark has nothing to do with my invention, and may be accomplished by any timing system suitable for the purpose. The explosions all take place within the single ignition chamber 43 and are caused by the single spark plug 46. Hence, the explosions take place one at a time, the several cylinders in succession being brought into communication with the ignition chamber and spark plug. The intake pipe 47 and exhaust pipe 48 are displaced from each other by an angle of 90 degrees; that is, each of them is displaced 45 degrees from a line extending horizontally through the center of the rotor.

The operation of my device is as follows: The parts being assembled and arranged as above indicated, and the intake pipe 47 connected up with the carburetor, the propeller 5 is turned by hand in a counterclockwise direction, according to Fig. 5; that is, in the direction in which the observer stands facing the propeller 11. The piston 32, adjacent to the bottom of the stator frame, is, 10 by the roller 42, brought into the lowermost position it can possibly assume. By its outward or downward movement it draws into the cylinder last mentioned, a charge of explosive mixture from the carburetor and 15 through the intake pipe 47. The turning of the rotor, in connection with the elliptically shaped track, forces the piston in question back into the cylinder and thus compresses the explosive charge. This explosive 20 charge, being thus compressed, is crowded back into the ignition chamber 43 until the piston passes the dead center, that is, arrives at such point that it coincides approximately with the shortest diameter of the 25 elliptical track. The spark plug 46 now explodes this charge, and consequently tends to drive the piston outward. The anti-friction wheel 39, by pressing outwardly against the now receding elliptical track 40, 30 turns the rotor as the piston in question is driven outward. As the piston reaches its outermost limit it also reaches its highest limit, and as the rotation is continued, the piston in question is forced back into the 35 cylinder, thereby scavenging the latter. Passing the dead center on the left, the weight and centrifugal force of the piston again draw it outward, causing it to create a partial vacuum, which is relieved by the 40 passage into it of another explosive charge from the carburetor. As the intake pipe 47 and the exhaust pipe 48 are displaced angularly in relation to each other by 90 degrees and the various parts are properly 45 proportioned, it is clear that the explosive charges, when first taken into the drum, are some little distance from the ignition chamber 43 and are never in communication with said ignition chamber except when completely disconnected from the intake and exhaust pipes. The several passages 28 are each in succession presented to the ignition chamber 43, and as each explosion takes 50 place, one and one only of the pistons is driven radially outward. Each cylinder, during each revolution of the rotor, undergoes four distinct cycles which include suction of gas, compression of the explosive 55 charge, expansion of the same, and scavenging of the cylinder. Meanwhile the rotation of the drum causes a continued and forced circulation of water through the drum and a consequent cooling of the cylinder bases. I do not show or describe any 60 mechanism for supplying electric current 65

to the spark plug 46, as apparatus of this kind is old and well known. Neither do I show the timing mechanism for the spark plug. In order to stop the engine the operator may either stop the flow of the fuel 70 to the carburetor or turn off the electric current used for energizing the spark plug, or simply turn the valve 44 so as to open it. Again, the valve 44 may be opened for the purpose of priming the ignition chamber, 75 releasing a charge under compression, or scavenging the ignition chamber and cylinders, cleaning the spark plug, slowing down the speed of the motor, or even stopping the motor in the event of the failure of other 80 stopping devices. In some instances it is desirable that the valve 44 be opened for the purpose of releasing compression of explosive mixture in the cylinders in order to facilitate starting of the motor by hand. 85

While for convenience I show one particular form only of anti-friction wheel 39, it will be understood that I do not limit myself to the precise details of this device, as it may be varied without departing from 90 the spirit of my invention. Neither do I limit myself to the precise form for any part shown, nor to any particular materials employed, the scope of my invention being commensurate with my claims. 95

Having thus described my invention, what I claim as new and desire to secure by Letters Patent is:—

1. In an internal combustion engine, the combination of an explosion mechanism including a revoluble member, a water chamber for said revoluble member, a set of stationary spiral tubes connected with said water chamber and adapted to receive water therefrom, said water being forced into said 100 spiral tubes by the motion of said revoluble member, a pipe extending into said water chamber and adapted to introduce water therein, as a means for returning said water 105 into said water chamber after said water has been cooled. 110

2. An internal combustion engine comprising a stator frame, a rotor revoluble relatively thereto, said rotor being provided with a water chamber, a stationary receptacle carried by said stator frame, a plurality of spiral pipes mounted upon said receptacle and provided with openings extending into said water chamber for the purpose of receiving water therefrom, a pipe connected 115 with said receptacle for receiving water from the latter, and means for supplying water continuously into said water chamber. 120

3. In a cooling construction for internal combustion engines, the combination of a 125 casing, a plurality of cylinders mounted thereon, said casing having passages communicating with the inner ends of said cylinders, said passages opening through the sides of said casing, a conduit leading 130

- through one end of said casing past the said 5
passages and terminating inside of said casing adjacent the opposite end, and discharge means adjacent the first-named end of said 10
casing.
4. In a cooling construction for internal combustion engines, the combination of a casing, a conduit leading through one end of said casing and terminating inside of said 15
casing adjacent the opposite end to supply cooling fluid thereto, a tubular body carried by the first-named end of said casing, and a plurality of pipes carried by said tubular body, said pipes having their ends bent away 20
from the axis of said casing, the drum being rotatable with respect to the pipes to discharge cooling fluid therethrough.
5. In a cooling construction for internal combustion engines, the combination of a casing having a tube mounted in one end thereof, a conduit passing through said tube and terminating inside of the casing adjacent the opposite end, and a plurality of pipes extending from the inner end of said 25
tube around said conduit, said pipes being bent away from the axis of said casing, the drum being rotatable with respect to the tube, whereby the conduit will supply fluid to the interior of the casing and the bent 30
pipes discharge the same therefrom.
6. A cooling construction for internal combustion engines, comprising a casing, cylinders radiating therefrom, passages connected with the inner ends of the cylinders and extending laterally therefrom into the casing 35

and opening through the sides of the latter, said passages being spaced apart from each other and outwardly from the axis of the casing, and separate means for supplying cooling fluid to and discharging it from the 40
said casing, one of the means consisting of a pipe extending axially of the casing and between the said passages.

7. A cooling construction for internal combustion engines, comprising a casing, cylinders radiating therefrom, passages connected with the inner ends of the cylinders and extending laterally therefrom into the casing and opening through the sides of the latter, said passages being spaced apart from 45
each other and outwardly from the axis of the casing, and separate means for supplying cooling fluid to and discharging it from the said casing, one of the means consisting of a pipe extending axially of the casing and between the said passages, said pipe terminating in an open end near one side of the casing and the other means consisting of a plurality of pipes having tangentially-disposed receiving ends within the portion of the casing opposite from the open end of the first 50
mentioned pipe, said casing and last mentioned pipe being relatively rotatable.

In testimony whereof I have signed my name to this specification in the presence of 55
two subscribing witnesses.

CHARLES LOUIS RAGOT.
